UNITED STATES PATENT OFFICE.

RICHARD W. JONES, OF SYRACUSE, NEW YORK.

DESIGN FOR A HARNESS-PLATE.

SPECIFICATION forming part of Design No. 30,592, dated April 18, 1899.

Application filed March 20, 1899. Serial No. 709,859. Term of patent 7 years.

To all whom it may concern:

Be it known that I, RICHARD W. JONES, a citizen of the United States, residing at Syracuse, in the county of Onondaga and State of New York, have invented a certain new and original Design for a Harness-Plate; and I do declare the following to be a full, clear, and exact description of the invention, such as will enable others skilled in the art to which it appertains to make and use the same.

The invention has relation to a new and original design for harness-plates; and it consists in a device of the shape and configuration shown in the accompanying drawings, in which—

Figure 1 is a perspective view, and Fig. 2 is a longitudinal sectional view.

The leading features of my design consist in an angular plate 1, one member of which is longer than the other and is provided with an outwardly-projecting transverse loop 2 and the apex of which is provided with a transverse aperture 3.

What I claim is—

The design for a harness-plate as herein shown and described.

In testimony whereof I have hereunto set my hand in presence of two subscribing witnesses.

RICHARD W. JONES.

Witnesses:

G. S. HIETZ,
C. W. REISINGER.
